DESIGN FOR A GLASS CIGARETTE OR LIKE CONTAINER

Herman Lowitz, Greensburg, Pa., assignor to American Glass Corporation, Greensburg, Pa., a corporation of Pennsylvania

Application June 13, 1945, Serial No. 120,052

Term of patent 14 years

(Cl. D85—2)

To all whom it may concern:

Be it known that I, Herman Lowitz, a citizen of the United States, residing in Greensburg, in the county of Westmoreland and State of Pennsylvania, have invented a new, original, and ornamental Design for Glass Cigarette or Like Container, of which the following is a specification, reference being had to the accompanying drawing, forming part thereof.

arette or like container showing my new design;

I claim:

The ornamental design for a glass cigarette or like container, as shown.

HERMAN LOWITZ.
